ATTORNEY

UNITED STATES PATENT OFFICE

WALTER MAJEWSKI, OF CHICAGO, ILLINOIS

HAIR WAVER

Application filed August 4, 1930. Serial No. 472,902.

This invention relates to hair wavers and the object of the invention is to provide a simple, novel and substantial construction by which the hair may be arranged evenly over 5 combs and a corrugated or undulated heating element and clamped in position while subjecting the hair to the action of the heat so as to effectively wave the same.

A further object of the invention is to provide means by which the hair may be waved alternately in opposite directions so as to give the usual wavy or sinuous effect, the device being capable of being moved along the 10 strands of hair in successively waving portions thereof until the waving operation is completed.

Another object of the present invention is to provide a hair waver embodying a fork rigidly affixed with one handle of the device 15 and a heating element rigidly attached to the other handle of the device, with which heating element a slidable plate may cooperate, which plate may be provided with combs arranged laterally of said heating element.

A still further object of the present invention is to generally improve the device shown in my co-pending application filed 20 January 6, 1930, Serial No. 418,700.

With the above general objects in view and 25 others that will appear as the nature of the invention is better understood, the same consists in the novel construction, combination and arrangement of parts hereinafter more fully described, illustrated in the accompanying 30 drawings and pointed out in the appended claims.

In the drawings forming a part of this application and in which like designating characters refer to corresponding parts throughout 35 the several views,

Fig. 1 is a side elevational view of the device;

Fig. 2 is a top plan view of the invention;

Fig. 3 is a transverse cross-sectional view 40 taken on line 3—3 of Fig. 1; and

Fig. 4 is a top plan view of a portion of the hair waver with the slidable plate extended.

Referring in detail to the drawings there is shown a fork 10 extending from an 45 S-shaped shank 11 which is bifurcated to

effect strips 12 and 13. Said strips 12 and 13 of shank 11 merge into solid handle portion 14 for receiving thereon handle 15 made of rubber, fiber or other insulating material.

The invention further includes an oblong 55 heating casing 16 which is receivable in between the tines of fork 10, when the device is closed, as seen on Fig. 3. On one face of said heating casing 16 a series of transverse corrugations 17 are made thereupon for providing retaining means for hair H which is transversely placed of said heating casing 16 and retained in position by means of fork 10 when the device is in closed position, as 60 seen on Fig. 3.

At the opposite side said heating casing 16 has a substantially rectangular plate 18 attached thereto, which is considerably wider than the width of the heating casing 16, effecting lateral flanges 19. Both said heating 65 casing 16 and plate 18 including flanges 19, merge into a hollow S-shaped shank 20 which passes between strips 12 and 13 and is pivoted therein by means of pin 21. The other end of said shank 20 is adapted to receive a hollow insulated handle 22. Cord of electric wires 23 is adapted to pass through said handle 22 and hollow shank 20 and enter within heating casing 16 and connect with the heating 70 element 24 within said heating casing. 75

Positioned upon the outer face of plate 18 and flanges 19 is a sliding plate 25, which, at its two lateral edges has perpendicular flanges 26 projecting therefrom. Said flanges 26 are brought towards heating casing 16 for effecting longitudinal elbows 27 at points at which said flanges 26 join with said sliding plate 25, for effecting longitudinal grooves adjacent the bases of said flanges 26 wherein the outer edges of flanges 19 are receivable, as 80 clearly seen on Fig. 3.

Thus, by this means plate 25 and flanges 26 are held in position upon plate 18 and flanges 19 and are guarded against lateral displacement, while at the same time being 85 permitted to make a longitudinal sliding movement with respect to said plate 18 and heating casing 16.

The free edges of said sides or flanges 26 are serrated to effect combs 28, which remain 90

outwardly and laterally of fork 10 when the device is in a closed position.

The ends of said sides 26 nearest to the handles 15 and 22 gradually converge towards strips 12 and 13, as at 29, and terminate in a pair of side guiding plates 30 contacting with said strips 12 and 13 and on a line with the pivot point 21.

The outer terminations of said guiding plates 30 are bridged and connected with handle 31 which extends outwardly of said guiding plates 30 and transversely thereof, said handle 31 being also transversely disposed of the plane passing through handles 15 and 22.

From the above description it will be seen that plate 25 as well as combs 28 and guiding plates 30 are adapted for longitudinal sliding movement with respect to the heating casing 16, plate 18, flanges 19 as well as fork 10.

When said combs 28 are shifted outwardly, or in the direction of the termination of fork 10, portion of handle 31 remaining within two guiding plates 30 will constitute a further movement limiting means when the same comes in contact with shanks 11 and 20 adjacent their pivot point 21. The outer end of plate 25 is provided with lug 32 which constitutes a further movement limiting means for combs 28 when said combs, including plate 25, are shifted in the opposite direction by manual operation of handle 31, said lug 32 contacting with the end of plate 18 and heating casing 16.

Plate 25 at its end nearest to the pivot point 21 is cut away from converging portions 29 of sides 26 and is made oval as at 33 to conform the shape thereof to said converging sides 29.

To operate the device handles 15 and 22 are manually shifted away from each other for bringing fork 10 away from its cooperative relation with heating casing 16 and combs 28, to the position shown by dotted lines on Fig. 1. Hair is placed upon said heating casing 16 and arranged between the teeth of combs 28. When the electricity supplied through wires 23 to heating element 24 is on, fork 10 is brought down towards flanges 19 by bringing handles 15 and 22 toward each other.

By this same operation the hair remaining above said flanges 19 will be brought by said fork 10 towards said flanges 19, as seen on Fig. 3. Thereupon said combs are shifted to either direction and longitudinally of said heating casing 16 and fork 10 by manually operating handle 31 while holding in the other hand handles 15 and 22. Portions of hair engaged by teeth of combs 28 will be drawn for effecting loops, curves or curls on a plane other than curls or curves caused by the heating casing 16, fork 10 and sides or flanges 26.

While there is described herein a preferred embodiment of the present invention, it is

nevertheless to be understood that minor changes may be made therein without departing from the spirit and scope of the invention as claimed.

What I claim as new is:

1. In a hair waver, a fork, a heating casing, said fork and said heating casing being in pivotal relation, flanges laterally extending from said heating casing, a plate positioned upon said flanges, and combs integrally formed with and perpendicularly extending from said plate, said combs at points of juncture with said plate having moldings for effecting grooves within which the adjacent edges of said flanges are receivable. 70

2. In a hair waver, a fork, a heating casing, said fork and said heating casing being in pivotal relation, flanges laterally extending from said heating casing, a plate positioned upon said flanges, combs integrally formed with and perpendicularly extending from said plate, said combs at points of juncture with said plate having moldings for effecting grooves within which the adjacent edges of said flanges are receivable, said plate and said combs being adapted for longitudinal sliding movement with respect to said heating casing, and means for limiting further movement thereof in either direction. 85

3. In a hair waver, a fork, a heating casing, said fork and said heating casing being in pivotal relation, flanges laterally extending from said heating casing, a plate positioned upon said flanges, combs integrally formed with and perpendicularly extending from said plate, said combs at points of juncture with said plate having moldings for effecting grooves within which the adjacent edges of said flanges are receivable, said plate and said combs being adapted for longitudinal sliding movement with respect to said heating casing, said combs at one of their ends gradually converge and merge into a pair of guiding plates which are adapted to contact with the sides of said fork substantially at and adjacent the pivot point of said fork and of said heating casing, and a handle bridging and connecting the free end of said guiding plates. 100

4. In a hair waver, a fork, a heating casing, said fork and said casing being in pivotal relation, flanges laterally extending from said heating casing, a plate positioned upon said flanges, telescopic retaining means between said plate and said flanges, permitting longitudinal movement of said plate with respect to said flanges, and combs formed with and perpendicularly extending from said plate. 110

In testimony whereof I affix my signature.

WALTER MAJEWSKI. 125
